UNITED STATES PATENT OFFICE.

STEPHEN P. HOLISH, OF CHICAGO, ILLINOIS.

COMBINATION-TOOL.

1,363,874.

Specification of Letters Patent. Patented Dec. 28, 1920.

Application filed April 5, 1920. Serial No. 371,468.

To all whom it may concern:

Be it known that I, STEPHEN P. HOLISH, a citizen of the United States, and a resident of Chicago, in the county of Cook and State 5 of Illinois, have invented new and useful Improvements in Combination-Tools, of which the following is a full, clear, and exact description.

My invention relates to improvements in 10 combination tools, and it consists in the combinations, constructions, and arrangements herein described and claimed.

An object of my invention is to provide a 15 novel form of combination tool which combines a plurality of tools ordinarily provided as separate implements, whereby the combination tool may be used in performing the different operations ordinarily performed by the plurality of tools with equal 20 effectiveness and with a great saving of time and labor.

A further object of my invention is the provision in a device of the type described, 25 of a saw blade having a single auxiliary member rigidly secured thereto, whereby a combination tool is formed comprising a handsaw, a square, a ruler or scale, and a bevel.

A further object of my invention is to provide 30 a device of the type described in which a portion of the handle is extended to serve as a guard for an auxiliary member, so that the device will not get out of order under service conditions.

A further object of my invention is to provide 35 a device that is simple in construction, which can be operated readily, and which is thoroughly practical commercially.

Other objects and advantages will appear 40 in the following specification, and the novel features of the invention will be particularly pointed out in the appended claim.

My invention is illustrated in the accompanying drawings, forming part of this application, in which—

Figure 1 is a side view of the device,

Fig. 2 is a top view of the same,

Fig. 3 is a view of the opposite side of 50 the device to that shown in Fig. 1.

Fig. 4 is a detailed perspective view of a fragmentary portion of the device, portions being broken away.

I am aware that combination tools comprising a plurality of separate tools have 55 been in common use for some time. Such tools have been found unsatisfactory, since

the different attachments are generally moved out of operative position when the tool is used under ordinary service conditions. The defects found in the devices in 60 common use are remedied in my device by the provision of the guard to protect the attachment and because of the fact that only one auxiliary member is required in order that a combination tool of the character described may be provided. This auxiliary member is rigidly secured directly to the saw blade and consequently the accuracy of the device is not impaired under service conditions as is the case in the devices in 70 use before my invention in which the auxiliary members are attached to the saw handle.

In carrying out my invention, I provide a saw blade 1 which may be of any desired 75 length and type. The lower longitudinal edge is formed with teeth 2, while the upper longitudinal edge is fashioned to provide a true straight edge 3. An opening 4 is formed through the saw blade adjacent one 80 end to provide a convenient means for hanging up the device when the same is not being used. The other end of the saw blade is disposed within a longitudinal slot 5 provided in a handle 13 and is maintained in 85 position by means of screws 6, or in any other approved manner.

An auxiliary member 7, which is preferably formed of metal in the shape of an angle-iron, is rigidly secured to the saw 90 blade 1 in any approved manner, as by rivets 9, as clearly shown in Fig. 4 of the accompanying drawings. The auxiliary member 7 is bent intermediate its length so that an end portion 8 adjacent the toothed 95 edge of the saw blade 1 extends laterally at an angle of 45° from the direction of the main portion of the auxiliary member 7. An opening 11 is formed through the saw blade 1 adjacent its upper edge and in such 100 a position, with respect to the end portion 8 of the auxiliary member 7, that one side of an article, such as a nail, will be in alignment with the end portion 8 when inserted through the opening 11. The auxiliary 105 member 7 is secured to the saw blade in such a manner that it forms one leg of a square of which the rear edge 3 of the saw blade 1 is the other leg. Consequently when the end portion 8 of the auxiliary attachment 7 is 110 placed against work, and the movement of the saw blade is limited by inserting an

article, such as a nail, through the opening 11, it will be found that the rear edge 3 of the saw blade diverges from the side of the work at an angle of 45° and that therefore 5 the end portion 8 of the auxiliary attachment 7 is in fact a bevel.

The handle 13 has a longitudinal portion 10 extending along the opposite side of the saw blade 1 from that to which the auxiliary 10 member 7 is attached. It will thus be seen that the auxiliary member 10 serves as a guard to protect the auxiliary member 7 and to prevent displacement of the same under 15 service conditions. The side of the handle 13, extending along the side of the saw blade 1 to which the auxiliary member 7 is attached, fits closely against the upright portion 15 of the auxiliary member 7.

When the auxiliary member 7 is formed 20 in the shape of an angle-iron, as illustrated in the accompanying drawings, one leg of the angle-arm is received within the slot 5 in the handle 13. A scale 12 is delineated along the upper edge of the saw blade 1 on 25 the side opposite that to which the auxiliary member 7 is attached.

From the foregoing description of the 30 various parts of the device, the operation thereof may be readily understood. When my improved combination tool is used, the operation ordinarily performed by a plurality of tools which are manufactured sep-

arately may be effectively performed. My improved combination tool is durable and can be used indefinitely. It occupies but a 35 small space and may be manufactured much more cheaply than the individual implements separately.

I claim:

A combination tool comprising a handsaw 40 blade having its rear edge formed into a true straight edge and having a scale delineated along its upper edge on one side, said saw blade being provided with an opening formed therethrough adjacent its free 45 end and with a second opening formed therethrough at a predetermined distance from the handle end, a saw handle rigidly secured to the saw blade, said saw handle having a longitudinal prolongation extending along the side of the saw blade upon which the scale is delineated, and an auxiliary member rigidly secured at right angles to the side of the saw blade opposite that having the scale delineated thereon, said 55 auxiliary member being disposed adjacent the handle and having the end portion thereon remote from the straight edge portion of the saw blade bent at an angle of 45° from the direction of the main portion 60 of the auxiliary member, thereby forming a bevel.

STEPHEN P. HOLISH.
